US00D719988S

(12) **United States Design Patent**
Runquist et al.

(10) **Patent No.:** US D719,988 S
(45) **Date of Patent:** ** Dec. 23, 2014

(54) **REAR CONNECTION INTER-FACE FOR A REDUCING ELEMENT OF A MATERIAL REDUCING MACHINE**

(71) Applicant: **Vermeer Manufacturing Company**, Pella, IA (US)

(72) Inventors: **Randy R. Runquist**, Knoxville, IA (US); **Clint Weinberg**, Pella, IA (US); **Keith Leon Roozeboom**, Pella, IA (US)

(73) Assignee: **Vermeer Manufacturing Company**, Pella, IA (US)

(**) Term: **14 Years**

(21) Appl. No.: **29/433,897**

(22) Filed: **Oct. 5, 2012**

(51) LOC (10) Cl. **15-09**

(52) U.S. Cl.

USPC **D15/123**

(57) **CLAIM**

The ornamental design for rear connection inter-face for a reducing element of a material reducing machine, as shown and described.

DESCRIPTION

FIG. 1 is a rear perspective view of a reducing element made according to our new design;

FIG. 2 is a rear side view of the reducing element of FIG. 1; FIG. 3 is a front side view of the reducing element of FIG. 1; FIG. 4 is a left side view of the reducing element of FIG. 1; FIG. 5 is a right side view of the reducing element of FIG. 1; FIG. 6 is a bottom side view of the reducing element of FIG. 1; and,

FIG. 7 is a top side view of the reducing element of FIG. 1.

1 Claim, 4 Drawing Sheets
